UNITED STATES PATENT OFFICE

KARL KINDL, OF GRAFENHAUSEN, NEAR NEUENBURG, GERMANY, ASSIGNOR TO ERNST
GIDEON BEK, OF PFORZHEIM, GERMANY

MACHINE FOR THE PRODUCTION OF MESH FABRIC AND CHAINS

Application filed June 1, 1927, Serial No. 195,633, and in Germany June 2, 1926. Renewed June 17, 1930.

This invention relates to machines for the production of chains, mail, ring mesh fabric and the like. It concerns more particularly machines of the type in which open wire rings or links carried on a plurality of supports are taken off simultaneously from the lower ends of the said supports, inserted in the links previously formed and then closed.

According to the method of operation of this type of machine for the production of mesh fabric, links are taken off simultaneously from a number of supports corresponding to the number of rings in the full width of the fabric. In this manner a whole row of open links may be suspended simultaneously in the row of links previously formed, (cf. German Patent No. 291,245).

The present invention has as its object certain improvements in this method of operation and in the devices for carrying it into effect.

One of the said objects is to provide in association with machines of the kind mentioned above a separate device which produces the open links, rings or cramps and at the same time piles the same, as formed, on a supporting member. This member, which constitutes a transferable support, is adapted to be readily removed from the device forming the open links and associated, carrying the said links, with magazine supports in the mesh making machine in such a manner that the latter supports may be filled with open links from the former while the machine is in operation. Since the link-forming device can turn out open links much faster than the mesh making machine can operate, one or a few of the former devices is sufficient to supply all the links for a mesh making machine of the kind mentioned with about fifty link supports.

A further material improvement according to this invention is the employment of pairs of needle-like tools for holding the downwardly suspended fabric in a manner similar to that in which the said tools have already been used in the production, according to the step by step method of manufacture, of rings and ring-formations (cf. Ger-

man Patents Nos. 274,722 and 262,367). These pairs of needle tools are of the known design by virtue of which they are adapted alternately to enter the links of the last formed of the successive rows and to hold the same during the operation of forming further links and incorporating them in the mesh fabric. The said tools are also given the same movement in the vertical plane as the known tools, but, in addition, execute a lateral displacement through half the width of a link after every fresh linking operation, this displacement corresponding to the similar displacement in known machines after the completion of a row. The employment of said tools is, moreover, considerably simplified since, according to the present invention they are independent of the link-forming tools which hitherto effected the feeding, cutting and preliminary bending of the wire. These latter tools restricted the available space which is an important drawback obviated in the mesh making machine according to the present invention in which there are only the tools for feeding and closing the completed links.

An advantage of the mesh making machine according to the present invention resides in the possibility of readily adapting it for the production of fabric with patterns in different colours. It is not only possible to produce differently coloured longitudinal strips simply by filling the different supports of a single row with different coloured links, but also to produce any desired patterns in the following manner:

Two or more rows of link supports are arranged one behind the other and the feed device for supplying the links from the lower ends of the supports to the points where said links are incorporated in the mesh is arranged to co-operate with the ends of all the rows of supports. If, now, these rows of supports are filled with open links of various colours and a jacquard-like pattern producing device is provided to control, in any desired manner, the removal of the links from the lower ends of the supports, that is to release one support of a set and maintain

the others closed, then patterns may be produced as desired.

The invention may also be readily modified for the production of a row of chains side by side.

This modification is arrived at if each link removed from the supports is suspended in a single completed chain link and not in two as in the case of the formation of a ring mesh fabric. The result is a number of chains, corresponding in number to the supports, which are produced side by side without the various gears and movements of the entire machine being altered at all materially.

15 Further improvements will appear from the description of the accompanying drawings in which:

Fig. 1 is a plan view of the device for producing the unclosed links,

20 Figs. 2, 3 and 4 illustrate the tools thereof in plan, front elevation and side elevation respectively,

Fig. 5 shows to a larger scale an open link at the moment at which it is formed,

25 Figs. 6 and 7 are elevations at right angles of the upper end of a transfer support to a larger scale,

Fig. 8 is a plan view of the mesh producing machine proper,

30 Fig. 9 a longitudinal section thereof showing the main parts,

Fig. 10 is a side elevation of a link support of the machine illustrated in Fig. 8,

35 Fig. 11 a plan view illustrating the manner in which supports are secured in the machine,

Fig. 12 is an elevation of a link support in position,

40 Fig. 13 a similar view illustrating how the links are removed from the support,

Fig. 14 is a sectional view at right angles to Figs. 12 and 13,

45 Figs. 15-18 illustrate the incorporation of a link in the mesh and the closing of the same,

Fig. 19 is a diagrammatic elevation of a machine for producing variously coloured patterns and

50 Fig. 20 is an elevation to a larger scale showing the means for controlling the removal from the supports of links of two different colours.

The links K are formed in a per se known manner. A length of wire D fed forward to be cut off by a knife is bent about a support 3, performing the function of a former, by the forward movement of a U-shaped forming tool 1 whereupon a forming tool 2 bends around the ends of the limbs of the U. These tools are, however, in contradistinction to those of known mesh making machines, of such design that a wide gap remains open in the blank (Fig. 5). In further contradistinction to known machines the support 3 is stationary and the removal of a finished link from the operating point is

effected by a forked sliding member 7 which by a downward movement pushes the link down on the support 3.

The lower end of the support 3 adjoins a transfer support 8 having precisely the same cross section as the former. Said transfer support is mounted at the bottom in a bearing 9 which is pressed upwardly by a spring 10. The row of finished links bears on a collar 11.

Figs. 6 and 7 illustrate the connection between the support 3 and the transfer support 8. The wedge-shaped end 13 of the support 3 is embraced by a similar recess 12 in the transfer support 8, the end of the transfer support 8 being bevelled at 14 so as to fit, in the plane perpendicular to the recess 12, in a corresponding recess in the support 3. In this manner the two supports are connected co-axially together and ensured against relative displacement.

The tools are driven as usual from a cam shaft A as clearly shown in Fig. 1. A cam 4a operates the cutter 4, a cam 1a the U-shaped former 1 and a cam 2a the former 2. An arm 6 holds the support 3. A carrier 17 for the forked sliding member 7 is operated by a cam 7a.

Operation of the machine results in filling the transfer support 8 with open links which rest freely thereon so that they are able to slide downwardly under their own weight and bear one on the other. Furthermore the movement of the forked sliding member 7 also has a positive effect on the movement and the arrangement closely one on the other of the links. After the transfer support 8 has been filled, its connection with the support 3 is broken by lowering the former against the pressure of the spring 10 until it can be removed from the machine.

This machine can by reason of its simple construction easily be operated at speeds of 500 revolutions per minute and more. All the tools may, moreover, be maintained in oil since the formation of the links and their movement along the support are effected positively and therefore the sticking of the links due to the oil will not be of the same importance as in the case of mail making machines.

It is clear that the machine may easily be constructed to produce simultaneously several links side by side, the same driving means being employed.

Referring to Figs. 8-13 of the drawings the magazine supports are mounted in the frame B of the mesh making machine on two cross beams C, C' disposed one above the other. For the sake of simplicity twenty-one such magazines only are shown, but they may number 50 or 60 depending on the maximum width of mesh fabric or mail to be produced.

The supports S are arranged with their upper ends S' free so that they can be sup-

plied without impediment with links from the transfer supports 8. Their securing means must therefore be distributed along the length of the supports without, however, interfering with the free fall of the links down the length of the support. For this purpose two swallow tail like projections s^1 are provided on each support S. Said projections are so narrow at their neck parts s^1 that the gap in the links K can readily slide past the same; the thicker portions s^2 thereof are let into suitable grooves in the cross beams C, C' and are secured in addition by means of screws s^3 to ensure exact positioning vertically (Figs. 10 and 11). At their upper ends S' the supports S are formed precisely as the lower ends of the supports 3 so that the transfer supports 8 may be readily centered thereon by hand and may be mounted securely with respect to two perpendicular axes. The links K are transferred by their own weight, if necessary with some slight assistance by hand, into their correct position on the supports S. Vibration by means of hammer blows may also be employed to ensure free fall.

The lower ends s^2 of the supports S extend so far through openings d in an upper guide plate D in the machine frame that their lower end surfaces are at a distance from a lower guide plate D' equal to the thickness of the wire of the links. The openings d correspond to the exterior shape of the open links K so that the latter can slide freely through them into guide passages D₂. Suspension slides E moving in the space between the guide plates D, D' are secured similarly to the teeth of a comb on a slide carrier E' which is guided in the machine frame and is given its movement by eccentrics E² on the shaft B'.

The manner in which the mesh is suspended on the obliquely guided comb of needles F is clear from Fig. 15. In the position illustrated in that figure an open link K has been inserted in two neighbouring rings (Fig. 16) preparatory to being closed in known manner (Fig. 17). Fig. 18 illustrates how the comb of needles F is withdrawn and the second comb F' moved forward to enter the newly closed links. The latter hang vertically as soon as the weight of the mesh comes to bear on them. The comb F' then makes a movement laterally through half the width of a ring in order to present, in the correct position, the next open links fed forward by the suspension slides to the row of rings suspended on said comb. The feed movement and the lateral movement of the combs F, F' are derived from cams.

Referring to Figs. 19 and 20 which illustrate a modification of the machine for the production of mesh fabric in several colours, two rows of supports S are provided and a locking device for the links is furnished at the

lower end of each support. In the arrangement illustrated in Fig. 20 one end h of a double lever H (left hand side) engages against the edge of the lower end surface of the support S and prevents the lowest link falling down into the path of the suspension slide E. The corresponding lever H on the right hand side is drawn back and inoperative. The suspension slide is given a stroke of such size that at every reciprocatory movement it passes below the two supports S, S. The levers H are controlled by cam discs H' and their movement may be regulated in any appropriate known manner by means of a jacquard mechanism or the like.

The same kind of machine may be used for the production of a row of independent chains only a few constructional adaptations being necessary for this purpose. The supports S are placed at a greater distance. One needle comb F is only employed moving vertically. Guides are provided for the chains coming down from the needles F guiding the chains at an angle sideward, to secure the proper hanging of the last link in the needle in a position to allow the free entrance of the next blank.

What I claim is:—

1. In the production of ring mesh fabric and chains in machines of the type in which rows of links are produced at a time, the method involving the steps of producing open links on a separate link forming device collecting and arranging said links as they are formed in co-incident relation on a temporary support, removing said support, together with the open links thereon, from the said device, into association with a magazine support in the mesh-fabric or chain making machine and feeding the links from said temporary support to the magazine support in said machine wherein they are operated on to form the mesh fabric.

2. A link forming device comprising in combination tools for shaping an open link about a former, means for the removal of the links shaped on the former and a removable transfer support which, in position, constitutes an extension of the former.

3. In a device as claimed in claim 2, providing the former of the said device and the magazine support of a mesh or chain making machine of the type set forth with means whereby a transfer support may be connected alternately with said former and said magazine support, the ends of the said members being made to fit one another to prevent lateral movement when associated one with another.

4. A transferring device for open links comprising a body having one end thereof shaped to seat itself into inter-engaging relation with the end of a support, which support is adapted to receive the open links from link bending devices, said body being shaped in

- cross-section substantially to the conformation of the open links and adapted to hold on the outer surface thereof a multiplicity of open links in co-incident relation, said transferring device being also adapted to seat itself in inter-engaging relation with a magazine of a machine for inter-engaging the links in order to feed the open ended links in a mass onto said magazine without disturbing their co-incident relation.
10. 5. In a machine for forming metal fabric having inter-engaging links, a link magazine shaped in cross-section substantially to the conformation of the links prior to inter-meshing, said magazine being adapted to support the links on the outer surface thereof and having a free end extending in proximity to a slideway through which the links are fed to the inter-meshing device, a cam-controlled lever normally adapted to restrain the column of links from sliding downwardly upon said magazine, said lever periodically moving out of the path of said links and permitting a single link to slide past the free end of said magazine.
15. 20. 25. In testimony that I claim the foregoing as my invention, I have signed my name at Stuttgart, this 16th day of May, 1927.
